PIVOTAL FITTING FOR PLAYGROUND APPARATUS

Isadore Horowitz, Shreveport, La., assignor to Universal
Manufacturing Co., Inc., Bossier, Shreveport, La.

Application September 14, 1953, Serial No. 26,780

Term of patent 14 years

(Cl. D54—2)

To all whom it may concern:

Be it known that I, Isadore Horowitz, a citizen of the United States, residing at Shreveport, in the Parish of Caddo, and State of Louisiana, have invented a new, original, and ornamental Design for a Pivotal Fitting for Playground Apparatus, of which the following is a specification, reference being had to the accompanying drawing, forming part thereof.

Fig. 1 is a bottom perspective view of a pivotal fitting for playground apparatus showing my new design;

Fig. 2 is a top plan view thereof;

Fig. 3 is a front elevational view; and
Fig. 4 is a side elevational view.

I claim:

The ornamental design for a pivotal fitting for playground apparatus, as shown.
